US0D1057459S

(12) **United States Design Patent** (10) **Patent No.:** **US D1,057,459 S**
(45) **Date of Patent:** **** Jan. 14, 2025**

(54) **LOUNGE CHAIR**

(71) Applicant: **Blu Dot Design & Manufacturing, Inc.**, Minneapolis, MN (US)

(72) Inventor: **Michael Carter**, Bloomington, MN (US)

(73) Assignee: **BLU DOT DESIGN & MANUFACTURING, INC.**, Minneapolis, MN (US)

(**) Term: **15 Years**

(21) Appl. No.: **29/825,383**

(22) Filed: **Jan. 31, 2022**

(51) LOC (15) Cl. **06-01**

(52) U.S. Cl.

USPC **D6/376**

(58) **Field of Classification Search**

CPC .. A47C 4/02; A47C 4/028; A47C 5/12; A47C 5/125

See application file for complete search history.

(57) **CLAIM**

The ornamental design for a lounge chair, as shown and described.

DESCRIPTION

FIG. 1 is a front upper perspective view of a lounge chair of Applicant's design;

FIG. 2 is a front elevational view thereof;

FIG. 3 is a rear elevational view thereof;

FIG. 4 is a first side elevational view thereof, the second side elevational view being opposite the first side elevational view and being a mirror image thereof;

FIG. 5 is a top plan view thereof; and,

FIG. 6 is a bottom plan view thereof.

Where included, broken lines showing environment or structure are for illustrative purposes only and form no part of the claimed design.

1 Claim, 6 Drawing Sheets
